T. J. THOMPSON

ELECTRIC ILLUMINATING DEVICE

Filed June 9, 1924

Inventor:

*Thomas J. Thompson,
By Dymforth, L. S., Chittenden, Vt., Atty.*

UNITED STATES PATENT OFFICE.

THOMAS J. THOMPSON, OF CHICAGO, ILLINOIS, ASSIGNOR TO STANDARD OIL COMPANY, OF WHITING, INDIANA, AND CHICAGO, ILLINOIS, A CORPORATION OF INDIANA.

ELECTRIC ILLUMINATING DEVICE.

Application filed June 9, 1924. Serial No. 718,826.

To all whom it may concern:

Be it known that I, THOMAS J. THOMPSON, a citizen of the United States, residing at Chicago, in the county of Cook and State 5 of Illinois, have invented a new and useful Improvement in Electric Illuminating Devices, of which the following is a specification.

My invention relates to an improvement 10 in the class of hand-operated devices for introduction of an incandescent electric lamp on one end of the device, in a battery-circuit thereon, into dark places to illuminate the latter.

15 My device, which is of peculiar and relatively inexpensive and simple construction, is especially designed for insertion into receptacles in cleaning them, and particularly into the steel barrels used for shipping 20 liquid petroleum products, such as gasoline, kerosene and the like, from the refinery. These barrels require thorough cleaning before filling, and for facilitating the work I have devised my medium to be withdraw- 25 ably inserted therein to illuminate them for ready and advantageous exploration of their interiors.

My device affords a convenient tool for this purpose, and one which is capable of being 30 constructed from materials which are usually discarded or scrapped about a refinery-plant as being of but little, if any, value. Thus, the tubular handle-forming battery-containing portion of the device consists 35 of short lengths of ordinary iron pipe, and the lamp-carrying tube of similar pieces of gas piping.

In the accompanying drawing—

Figure 1 shows the device by a view in 40 elevation, and

Figure 2 is an enlarged broken and mainly sectional view of the same, showing the parts substantially in their actual dimensions.

45 The tubular handle 3, which is shown at 3^a in Fig. 1 to be longitudinally corrugated to afford a firm hand-grip, is preferably a section of iron pipe with its ends threaded for screwing thereon closing caps 4 and 5. 50 A relatively narrow tube 6, which is preferably a piece of ordinary gas-pipe of suitable length, say three feet or thereabout, is screwed at one end into the cap 5. A bushing 7, secured to extend through the wall 55 of the cap 5 in position diametrically op-

posite the connection therewith of the pipe 6, carries within the cap a hollow body 8 of insulating material divided by a perforated partition 8^a into chambers 8^b and 8^c. A spring-pressed push-button 9 works 60 in the chamber 8^b through the bushing 7 and partition 8^a, and projects into position to be conveniently operated by the user of the device when held at the handle 3 in one hand. In the handle is confined the source 65 of electrical energy, represented as a pair of ordinary dry storage-batteries 10, 10 in electrical end-to-end contact, the terminal 11 of the leading battery engaging a contact-button 12 carried on a disk 13 of insulating material confined about its edge between the adjacent end of the tubular handle 3 and a flange 12^a in the cap 5.

On the advance-end of the pipe 6 is provided a cage-like shield 14 terminating in an abutment-ring 14^a and containing and protecting the bulb 15 of an incandescent electric lamp in its usual socket, with the terminals in which latter insulated wires 16 and 17 are connected, these wires passing 80 through the pipe 6 and projecting into the cap 5. The electrical circuit is formed by an insulated wire 16^a connecting the rear-most battery 10 with the end in the cap of the wire 16, of which the wire 16^a is a continuation; and through the base of the body 8 there extend into the chamber 8^c the similar spring-contact terminals 18, 18 to be engaged by the push-button, the wire 17 being connected with the projecting end of 90 one of these arms, the corresponding end of the other arm being connected with the button 12 by a section of insulated wire 18^a.

To apply the device to its purpose, the user holding it at the handle 3 inserts the 95 pipe 6 into the interior of the object to be illuminated, and closes the circuit at the push-button 9 to light the lamp.

I realize that considerable variation is possible in the details of construction of my improved device thus shown and described, and I do not intend to limit my invention thereto except as pointed out in the appended claims, in which it is my intention to claim all the novelty inherent in my invention as broadly as permissible by the state of the art.

I claim:

1. An electric illuminating device comprising a handle-forming battery-enclosing 110

- tube, caps closing the ends of the tube, one of said caps carrying a chambered body of insulating material and being provided with openings, a pipe seated in one of said openings and extending at an angle to the cap, terminals in said cap, a circuit-closing push-button extending through an opening in the cap and adapted, when pressed inwardly, to contact with said terminals, a lamp carried by the free end of the tube, and conducting wires leading from said lamp to the terminals, battery and button.
2. An electric illuminating device comprising a handle-forming tube containing a battery, a cap on an end of said handle, a contact-button confined in the cap against an adjacent terminal of the battery, a pipe extending at an angle to the handle from the cap thereon and carrying an incandescent electric lamp on its advance-end, a chambered body of insulating material in said cap, a spring-pressed push-button at one end of said body, terminals extending into said body through its opposite end and with one of which said button is electrically connected, and conducting wires leading through the pipe and respectively connecting said lamp with the other terminal and through the battery with said button.
3. An electric illuminating device comprising a handle-forming tube containing a battery, a cap on an end of said handle, a disk of insulating material confined by the cap against said end of the tube and carrying a button contacting with the adjacent battery-terminal, a pipe extending at an angle to the handle from the cap thereon and carrying a shield-surrounded incandescent electric lamp on its advance-end, push-button circuit-closing means including said button in the cap, and conducting wires leading through the pipe and respectively connecting the lamp with one terminal of said circuit-closing means and indirectly with the other terminal thereof through the battery and said button.

THOMAS J. THOMPSON.
